UNITED STATES PATENT OFFICE.

SWAN OLSON, OF MARION, NORTH DAKOTA.

TRACE-CARRIER.

1,103,373.

Specification of Letters Patent. Patented July 14, 1914.

Application filed March 14, 1912. Serial No. 683,903.

To all whom it may concern:

Be it known that I, SWAN OLSON, a citizen of the United States, and post office at Marion, Lamoure county, State of North Dakota, have invented certain new and useful Improvements in Trace-Carriers, of which the following is a specification.

This invention relates to trace carriers.

The object of the invention resides in the provision of a trace carrier which will be simple in construction, cheap to manufacture and which will efficiently perform the offices for which it is intended.

With the above and other objects in view the invention consists in the details of construction and in the arrangement and combination of parts to be hereinafter more fully described and particularly pointed out in the appended claim.

In describing the invention in detail reference will be had to the accompanying drawings wherein like characters of reference denote corresponding parts in the several views, and in which—

Figure 1 is a perspective view of a trace carrier constructed in accordance with the invention. Fig. 2, a longitudinal section of the trace carrier; Fig. 3, a transverse section taken just forward of the pivot of the locking arm of the trace carrier, and Fig. 4, a longitudinal section of a slightly modified form of the invention.

Referring to the drawings the trace carrier is shown as comprising a body 10 provided at each end with a loop 11, said loops being disposed in alinement with each other to permit the passage of a suitable portion of a harness therethrough. Mounted centrally in the body 10 is a stud 12 which projects on the same side of the body as the loops 11 and is adapted to be detachably engaged in a perforation in the harness part which passes through the loop 11. When the stud 12 is engaged in a perforation in the harness the trace carrier is locked against sliding movement thereon, said carrier being at other times capable of longitudinal adjustment on that portion of the harness engaged through the loops 11. The body 10 is provided at one end with a longitudinal slot 13 and formed on said body on each side of the slot 13 is an ear 14. Bridging the slot 13 is a leaf spring 15 which extends longitudinally of the body 10 and has one end anchored to said body as at 16. The end walls of the slot 13 are inclined as at 17

so that when the spring 15 is depressed centrally the inclined end walls 17 of the slot will form a substantial support for same. Formed on the body 10 at the end thereof remote from the ears 14 is a supporting arm 18 the outer end of which is curved inwardly as at 19. Pivotedly mounted between the ears 14 is a locking arm 20 which has its inner end provided with spaced cam extensions 21 and 22 adapted for coöperation with the spring 15 as said arm 20 is moved on its pivot. Under normal conditions both of the cam extensions 21 and 22 will engage the spring 15 and the latter will thereby serve to hold the free end of the arm 20 normally in the position shown in Figs. 1 and 2. To apply a trace within the holder the free end of the arm 20 is moved toward the body 10 and the cam extension 22 will engage the spring 15 and tension the latter. After the trace is inserted in the holder the arm 20 is released and the spring 15 will bring the same back to normal position. To remove the trace from the carrier the free end of the arm 20 is forced outwardly or away from the body 10 which will bring the cam extension 21 into engagement with the spring 15 and tension the latter. When the trace has been removed the arm 20 is released and the spring 15 will react to return said arm to normal position. Movement of the free end of the arm 20 away from the body 10 is limited by means of a stop 23 formed on one ear 14 and adapted to be engaged by a shoulder 24 formed on the arm 20 in a desired position.

In the modified form of the invention the outer end of the spring 15 is anchored to the body 10 by a pin 15' and this pin also serves as a stop for limiting the movement of the free end of the arm 20 away from the body 10, said pin being adapted to be engaged by an extension 20' formed on the inner end of the arm 20.

What I claim is:—

A trace carrier comprising a body having means for connection to a harness part and having a longitudinal slot in one end, a supporting arm on the other end of the body and directed inwardly thereof, spaced ears on said body on opposite sides of the slot respectively, a locking arm pivoted at one end between said ears, spaced cam extensions on the pivoted end of said locking arm, a leaf spring bridging said slot and coöoperating with said cam extension to normally hold

the free end of the locking arm in alignment with the free end of the supporting arm and permitting pivotal movement of the locking arm in either direction, a shoulder formed on the outer edge of the locking arm, and a bridge connecting said ears and adapted to be engaged by said shoul-

der to limit the movement of the locking arm in one direction.

SWAN OLSON.
